Primary Examiner — Ian Simmons*Assistant Examiner* — Mark A Cavanna(74) *Attorney, Agent, or Firm* — Banner & Witcoff, Ltd.(57) **CLAIM**

The ornamental design for a connector for probe for an ultrasonic diagnosis apparatus, as shown and described.

DESCRIPTION

FIG. 1 is a perspective view (1) of a connector for probe for an ultrasonic diagnosis apparatus showing my new design, FIG. 2 is a perspective view (2) thereof, FIG. 3 is a perspective view (3) thereof, FIG. 4 is a front elevational view thereof, a rear elevational view being a mirror image thereof, FIG. 5 is a top plan view thereof, FIG. 6 is a bottom plan view thereof, FIG. 7 is a left side elevational view thereof; and, FIG. 8 is a right side elevational view thereof.
